SCREW THREAD CLEANER

Filed Jan. 23, 1930

INVENTOR.
Robert M. Cornett
BY Warren W. House,
His ATTORNEY.

Witness:
H. Vernon Olson

UNITED STATES PATENT OFFICE

ROBERT M. CORNETT, OF KANSAS CITY, MISSOURI

SCREW-THREAD CLEANER

Application filed January 23, 1930. Serial No. 422,964.

My invention relates to improvements in screw thread cleaners.

It is adapted for use on machines which are subjective to use exposing them to large amounts of dirt, dust or other matter which forms accretions on screws of the machines and makes them difficult to turn, or for nuts on them to turn. Wood working machines are particularly liable to have such accretions accumulate on their screws, such as screws used to support vertically adjustable tables.

The object of my invention is to provide simple, cheap, novel means for automatically 15 cleaning the threads of screws, which cleaning means is adapted for attachment to stationary or rotating parts fitted on stationary or rotating screws. My invention also provides for nuts fitted with my improvement 20 and adapted for general marketing separate from screws with which they are adapted to be used.

The novel features of my invention are hereinafter fully described and claimed.

25 In the accompanying drawing which illustrates my invention,

Fig. 1 is a plan view of an internally threaded machine member engaged by a screw, shown in cross section, and two of my 30 improved thread cleaners mounted on said member and engaging the screw, the screw threads being of the square type.

Fig. 2 is a side elevation, partly broken away of what is shown in Fig. 1.

35 Fig. 3 is a section on the line 3—3 of Fig. 2.

Fig. 4 is a view similar to Fig. 2, showing V type threads.

Fig. 5 is a top view of a nut mounted on a screw and provided with two of my improved 40 thread cleaners.

Fig. 6 is an enlarged elevation of one of the cleaning devices shown in Figs. 1 to 3.

Fig. 7 is an enlarged side elevation of one of the cleaning devices shown in Fig. 4.

45 Fig. 8 is an end view of the device shown in Fig. 7.

Fig. 9 is an enlarged side elevation of the cleaning device having a cylindrical shank and adapted for use with square threads.

50 Fig. 10 is a side elevation of the device

having a cylindrical shank and adapted for V type threads.

Fig. 11 is an end view of the device shown in Fig. 10.

Similar reference characters designate 55 similar parts in the different views.

1 designates a vertical screw fitted in an internally threaded member 2, which may be a part of a machine, and which may be rotatable, or the screw may be rotatable in said member.

In Figs. 1, 2 and 3 the threads of the screw and member 2 are shown as of the square type. Two holes 3 are provided, one in the upper and one in the lower side of the member 2, the outer end portions of said holes 3 being larger in diameter than the inner portions thereof.

Two cleaning devices are provided, each of which has a vertical shank 4, which is 65 slidably and rotatably fitted in one of the holes 3. Each cleaning device has at the outer end of the shank 4 a laterally extending portion 5 adapted to extend between the threads of the screw 1 and to travel therebetween for the purpose of cleaning the threads. The inner portion 5 is shaped to fit the groove 70 between the threads. In the form shown in Figs. 1 to 3, the inner end of the portion 5 is square in cross section. In the form shown in Fig. 4, the corresponding portion, designated by 5' is wedge shaped to fit the V shaped groove between the threads of the screw, designated by 1'.

The shank 4 of each device is fitted to slide 85 and turn in the inner smaller end of the hole 3 in which it is mounted.

The member 2 is provided with two horizontal threaded holes respectively intersecting the enlarged outer portions of the two holes 3, Figs. 1 to 3.

Respectively fitted in these two threaded holes are two set screws 6, the inner ends of which bear respectively against the adjacent shanks 4, which are respectively provided with recesses 7 in which the inner ends of the screws 6 are respectively disposed, and which serve to prevent the cleaning devices 95 from slipping out of the holes 3, when the 100

screws 6 are not tightly bearing against them.

By tightening the screws 6, the portions 5 of the cleaning devices are made to bear against the screw 1 between the threads thereof, whereby when there is relative turning in either direction of the member 2 or of the screw 1, the threads of the latter will be cleaned of accretions. The screws 6 are respectively provided with lock nuts 8 which bear against the member 2 and hold the screws from accidental turning.

By having the shanks 4 slidable and rotatable in the holes 3, the shanks are easily and quickly slid into or out of the holes 3.

In applying the cleaning devices, the shanks 4 are slid into the holes 3 and then turned until the portions 5 enter between the threads of the screw 1, following which the set screws 6 are turned so as to respectively force the portions 5 tightly against the screw 1, after which the lock nuts 8 are tightened, Figs. 1 to 3.

In the form shown in Fig. 4, the construction is similar to that described and shown in Figs. 1 to 3, excepting that the screw 1' and the internally threaded member 2', in which the screw 1' is fitted, are provided with V type threads, and the portions 5' of the thread cleaning devices have their inner ends wedge shaped, as before stated, so as to fit between the threads of the screw 1'.

In the form shown in Figs. 4, 5, 7 and 8, the member 2' is a nut mounted on the screw 1', the upper and lower ends of the nuts having the vertical holes 3, corresponding to the holes 3 in the member 2, of Figs. 1 to 3, in which are respectively fitted the shanks 4 of the cleaning devices, and set screws 6 are respectively fitted in threaded holes in the nut and respectively bear on the shanks 4 for forcing the portions 5' against the screw 1' between the threads of the latter, as has been described with reference to the set screws 6 in Figs. 1 to 3.

The screws 6 in Figs. 4 and 5, are respectively provided with lock nuts 8 bearing against the nut member 2'.

The shanks 4, as shown in Figs. 1 to 7 are square in cross section. This permits the screws 6 to reliably hold the shanks from turning in the holes 3 even though the shanks were not provided with the recesses 7, which could be eliminated, in the forms shown in Figs. 1 to 8, with the elimination, however, of the function of holding the shanks 4 from slipping out of the holes 3, when the set screws are not tightened sufficiently to bind on the shanks, as before the screws 1 and 1' are fitted in the members 2 and 2' respectively.

In the forms shown in Figs. 9, 10 and 11, the shanks 4' are circular in cross section, so that the side recesses 7 therein are required for receiving the set screws, so as to hold the shanks 4' from turning, as well as to

hold them from slipping out of the holes in which they are mounted.

In the form of cleaner shown in Fig. 9, the inwardly extending portion 9, is shaped to fit in a square type thread, and the portion 10 of the cleaner shown in Figs. 10 and 11, is wedge shaped at its inner end to fit a V type thread.

The cleaners shown in Figs. 9 and 10 may be substituted for those shown in Figs. 2 and 4 respectively, and are operable in a like manner.

Other modifications, within the scope of the appended claims, may be made without departing from the spirit of my invention.

What I claim is:

1. In a screw thread cleaner, the combination with a screw and an internally threaded member fitted thereon, of a device rotatable on and slidably fitted to and adjustable inwardly on said member to a thread cleaning position between the threads of said screw, and means for forcing the said device to said position and for holding said device from turning on said member.

2. In a screw thread cleaner, the combination with a screw and an internally threaded member fitted thereon and having a hole, of a device having a shank slidably fitted in said hole, said device being adjustable inwardly to a thread cleaning position between the threads of said screw, and a set screw in said member bearing on and adapted to force said device to said position.

3. In a screw thread cleaner, the combination with a screw and an internally threaded member fitted thereon and having a hole, of a device slidably and rotatably fitted in said hole and adjustable inwardly to a thread cleaning position between the threads of said screw, and a set screw in said member bearing on said device and adapted to force said device to said position and to hold said device from sliding or turning in said hole.

4. In a screw thread cleaner, the combination with a screw and an internally threaded member fitted thereon and having a hole, of a device having a shank slidably and rotatably fitted in said hole and having a lateral recess, said device being adjustable inwardly to a thread cleaning position between the threads of said screw, and a set screw in said member and entering said recess and bearing on said shank for holding the latter from turning and from sliding and adapted to force said device to said position.

5. In a screw thread cleaner, the combination with a screw and an internally threaded member fitted thereon and having a hole, of a device having a shank other than circular in cross section slidably and rotatably fitted in said hole, said device being adjustable inwardly to a thread cleaning position between the threads of said screw, and a set screw in said member bearing against one side of said

shank and adapted to force said device to said position and to hold the shank from turning.

6. In a screw thread cleaner, the combination with a screw and an internally threaded member fitted thereon and having a hole having an enlarged outer portion, of a device having a shank slidably and rotatably fitted in the smaller portion of said hole, said device being adjustable inwardly to a thread cleaning position between the threads of said screw, and a set screw in said member bearing against said shank in the enlarged portion of said hole and adapted to force said device to said position.

15 In testimony whereof I have signed my name to this specification.

ROBERT M. CORNETT.
